(57) **CLAIM**

The ornamental design for container with wooden design, as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view a first side and a first end of the container;

FIG. 2 is a perspective view a second side and the first end of the container in FIG. 1;

FIG. 3 is an elevational end view of the first end of the container in FIG. 1, a second end of the container being the same as the first end; and,

FIG. 4 is an elevational side view of the first side of the container in FIG. 1, the second side of the container being the same as the first side.
